DESIGN FOR A DISPLAY PLATE FOR AUTOMOBILES OR SIMILAR ARTICLES

Peter B. Searcy, Austin, Tex.

Application October 28, 1947, Serial No. 142,171

Term of patent 14 years

(Cl. D14—6)

To all whom it may concern:

Be it known that I, Peter B. Searcy, a citizen of the United States, residing at Austin, in the county of Travis and State of Texas, have invented a new, original, and ornamental Design for a Display Plate for Automobiles or Similar Articles, of which the following is a specification, reference being had to the accompanying drawing, forming a part thereof.

Figure 1 is a face view of a display plate for automobiles or similar articles, showing my new design.

Figure 2 is a top edge view.

Figure 3 is an end view.

I claim:

The ornamental design for a display plate for automobiles or similar articles, as shown.

PETER B. SEARCY.
